GATE, TERRITORY OF NEW MEXICO.

PEN AND PENCIL RACK.

No. 815,241.

Specification of Letters Patent.

Patented March 13, 1906.

Application filed August 23, 1905. Serial No. 275,355.

To all whom it may concern:

Be it known that I, FRANZ WENKE, a citizen of the United States, residing at Fort Wingate, McKinley county, Territory of New Mexico, have invented a certain new and useful Improvement in Pen and Pencil Racks, of which the following is a specification:

My invention relates to a new and useful improvement in pen and pencil racks, and 10 has for its object to provide a pen and pencil rack in which the pens and pencils will be held securely in the rack, so that they will not become displaced no matter which way the rack is turned, but are instantly released 15 by pressing the proper key, the pen or pencil falling downward into a receiver.

With these ends in view this invention consists in the details of construction and combination of elements hereinafter set 20 forth and then specifically designated by the claims.

In order that those skilled in the art to which this invention appertains may understand how to make and use the same, the 25 construction and operation will now be described in detail, referring to the accompanying drawings, forming a part of this specification, in which—

Figure 1 is a vertical cross-section through 30 my improved device, the receiver being shown folded in dotted lines; Fig. 2, a front elevation of the rack.

The rack consists of the two side plates A, the front edges of which are preferably inclined downward and forward. These two side plates are joined together at the top by a plate B and at the bottom by a plate C. Of course the construction of this framework can be varied—as, for instance, the side 40 plates may be in skeleton form and may be joined together by rods instead of plates.

D represents shafts extending transversely across the rack arranged one below the other and journaled in side plates. To each end 45 of each shaft is secured a disk E, said disk lying close against the inside of the side plates A.

F represents levers pivoted at their inner ends to the disks E near the periphery of said 50 disks.

G represents notches formed in the forward edge of the side plates A, the lower wall of said notches being inclined down-

ward and outward, the upper wall being undercut, if desired.

The levers F are pivoted intermediate of their ends to the side plates at the point F'. The outer ends of the levers are turned up slightly, and these levers operate in conjunction with the notches G to hold the pen and 60 pencils in place.

H represents key-rods extending downward through the top plate B, each of said rods being provided with a key H' upon the upper end above the top plate B. Each of the rods H 65 may be pivoted directly to a disk E upon the opposite side of the shaft D from the point where the lever F is pivoted. The intermediate key-rods will be pivoted to cranks or disks E', connected to the shafts D, each key- 70 rod adapted to operate a different shaft and so connected that when the key is depressed the shaft D will be rotated, so as to throw the outer end of the lever F downward. Springs I are interposed between the top plate B and the keys H', tending to press the key-rods upward, and thus tending to throw the outer end of the levers F upward, and these levers are limited in their upper movement when no 75 pen or pencils are in the rack by the stops J. 80

When the pen or pencils are in the rack, they are held in the notches G between the upper wall of the notches and the curved end of the levers F.

In Fig. 1 I have shown a pen or pencil in 85 the top and lower notch. The next to the top notch is vacant, and the next to the lower lever is operated in the act of releasing the pen or pencil. It will thus be seen that when the key is depressed the lever is moved to 90 such a position that the pen or pencil is free to fall out of the notches downward upon the curved receiver K. Said receiver may be hinged to the framework and folded upward against the same, as shown in dotted lines in 95 Fig. 1.

In order to place a pen or pencil in the rack, it is only necessary to press the pen or pencil downward upon the end of the levers, when the pencil will slip easily into its place, and 100 once in place it cannot be accidentally removed no matter how much the rack is moved about. This is a great advantage, especially for desks of business men, for it avoids any possibility of a pen falling downward upon a 105 written sheet and blotting the same when the

rack is moved or if the coat-sleeve accidentally touches the pen while in the rack. Another great advantage is that a particular notch can be used for the red-ink pen, another notch for the black-ink pen, another one for a color pencil, and another for the black lead-pencil, and the keys can be marked to indicate these different articles, so it is only necessary to press the right key to obtain the proper article. Of course there can be any number of notches desired, and the device can be provided with ink-well cells upon each side, if so desired, and can be made in any desired shape and ornamented to please the user, and it will be observed that instead of the disks E and E' ordinary crank-arms can be used. Therefore I do not wish to be limited to the exact construction here shown, as slight modifications could be made without departing from the spirit of my invention.

Having thus fully described my invention, what I claim as new and useful is—

1. In a pen and pencil rack, side plates suitably connected together, the forward edge of said side plates provided with a series of notches in which the pen or pencils are adapted to fit, the lower wall of said notches being inclined downward and forward, levers pivoted to the side plates, the forward end of said levers adapted to engage the under side of the pen or pencil and hold them in the notches, springs adapted to hold the outer end of said levers upward against the pen or pencil, a series of keys, one for each set of notches, means for depressing the levers so as to allow the pen or pencils to roll out of the notches when the keys are depressed, as and for the purpose specified.
2. In a pen or pencil rack, two side plates suitably connected together, said side plates provided with a series of notches in their forward edge, the lower wall of each of said notches being inclined downward and forward, the upper wall being undercut, levers pivoted to the side plates, the forward end of said levers being curved upward and adapted to contact the under side of the pen or pencil

and hold said pen or pencil against the upper wall of the notch, the forward end of the levers extending beyond the forward edge of the side plates, springs tending to force the levers upward against the pen or pencil, stops for limiting the upward movement of the levers when the notches are vacant, a series of keys, one for each set of levers, means for depressing said levers when the keys are depressed so as to allow the pen or pencil to fall out of the notches, a curved receiver connected with the rack for receiving the pen or pencil falling out of the notches, as and for the purpose specified.

3. In a pen or pencil rack, two side plates suitably supported, said side plates provided with notches in their forward edge, the lower wall of said notches being inclined downward and forward, levers pivoted to the side plates intermediate of their ends, the forward end of said levers being curved upward and adapted to come in contact with the lower surface of the pen and pencil and hold the pen or pencil in the notches, the forward end of said levers extending beyond the side plates, stops for limiting the upward movement of the levers when the notches are vacant, a series of shafts journaled in the side plates, two disks or cranks upon each shaft, to the outer end of which the rearward end of the levers are pivoted, a series of keys, key-rods extending downward, disks connected to the shafts, to the outer edges of which the key-rods are connected upon the opposite side of the shafts from the point where the levers are connected, springs interposed between the framework and the keys tending to force the key-rods upward, and a curved receiver hinged to the framework adapted to receive the pen or pencil falling from the notches, as specified.

In testimony whereof I have hereunto affixed my signature in the presence of two subscribing witnesses.

FRANZ WENKE
